METHOD FOR THE MANUFACTURE OF METAL CARBONYLS

John V. Fill, Dobbs Ferry, N. Y., assignor to
Maguire Industries, Incorporated, New York,
N. Y., a corporation of Delaware

Application May 22, 1941, Serial No. 394,655

3 Claims. (Cl. 23—203)

This invention relates to method and apparatus for the manufacture of metal carbonyls and is of special value in the making of ferro-penta-carbonyl (Fe(CO)₅) for use in making finely divided iron for magnetic cores.

An important object of the invention is to provide a continuous method for making metal carbonyls. In accordance with the invention, carbon monoxide gas and finely divided sponge metal are continuously fed to a reaction chamber at controlled rates while gaseous ferro-pentacarbonyl and any excess of metal are continuously withdrawn from the chamber. The metal carbonyl gas is condensed to a liquid as it is withdrawn from the chamber and this liquid is separated from any excess metal so as to provide a continuous supply of the liquid carbonyl.

Another object of the invention is to provide for a very complete and rapid reaction between finely divided sponge metal and carbon monoxide gas. In accordance with the invention, finely divided sponge metal is introduced into the reaction chamber in a jet of carbon monoxide gas and the rapid stream of gas containing the metal is impinged upon another stream of carbon monoxide gas moving rapidly in another direction. This exposes all surfaces of the metal particles to the gas and results in a very rapid reaction.

In order that this and other features of my invention may clearly be understood, I will describe in detail a specific method embodying my invention carried out by means of the apparatus embodying my invention which is illustrated in the accompanying drawing in which:

Fig. 1 is a diagrammatic sectional elevation of the complete apparatus;

Fig. 2 is a horizontal section on the line 2—2 of Fig. 1 showing the direction in which the injection nozzles are pointed; and

Fig. 3 is a fragmentary horizontal section of part of the wall of the reaction chamber showing a different nozzle arrangement.

In the form illustrated in Figs. 1 and 2, two nozzles 11, 12 project into a reaction chamber 10. The nozzles are provided with needle valves 13, 14 to regulate the flow through them.

Carbon monoxide gas under high pressure is fed to each nozzle. I find it most desirable to have this gas under pressure of from 600 to 700 pounds per square inch, although it is possible to operate the apparatus with any pressure between 200 and 1,000 pounds per square inch. The compressed gas for the nozzle 11 is introduced through a pipe 15 connected to the nozzle 13 by a pipe 16, while the compressed gas for the nozzle 12

is introduced through a pipe 17 connected to the nozzle by a pipe 18. The pipes 17 and 15 are connected with sources of compressed carbon monoxide gas not shown, as the source from which the gas is derived is not material to this invention. In practice, I find it convenient to introduce into one of the supply pipes, for example, pipe 17, carbon monoxide gas derived from the decomposition of metal carbonyl carried out as shown in my co-pending application Serial No. 394,656, filed May 22, 1941, and to supply the pipe 15 with carbon monoxide gas from a different source. In order that carbon monoxide gas derived from two different sources may be projected by the nozzles 11 and 12 at the same velocity, a pressure-regulating valve 19 is provided in the pipe 17 and a pressure equalizing pipe 20 connects the two nozzles.

Finely divided sponge iron pulverized to 300 mesh and free from oxide is fed into the reaction chamber in the jet produced by the nozzle 11. Any powder entraining apparatus such as is used in injecting powdered coal into a furnace by means of an air jet may be used to entrain powdered sponge iron into the stream of compressed carbon monoxide gas entering the nozzle 11. In the form illustrated in the drawing, the powdered sponge iron is contained in a divided hopper 21 connected with an injector 22 introduced between the pipe 15 and the pipe 16. The hopper 21 is provided with two gates 23 one of which is closed so that one-half of the hopper may be refilled with powdered sponge iron while powdered sponge iron is being drawn into the injector 22 from the other half of the hopper. This permits refilling the hopper without interrupting the operation. A sump 24 and a collector 25 may be provided beyond the injector 22 to collect any large particles of the iron which are not entrained by the gas jet in the injector.

The jets of gas from the injectors 11 and 12 produce rapidly moving streams of gas directed in opposite directions. The two streams impact upon each other as shown in Fig. 2. This causes extremely effective contact between all the surfaces of the iron particles and the gas and results in a rapid reaction between them which produces ferro-carbonyl gas.

The lower portion 26 of the reaction chamber 10 is funnel-shaped and the bottom of the chamber is connected to a vertical outlet pipe 27 which leads into a cooling chamber 28 provided with a cooling coil 29. The ferro-carbonyl gas is condensed to liquid ferro-carbonyl in this chamber and collects as liquid in the bottom of the cham-

ber whence it runs through a pipe 38 into a separator 35 from which it is continuously withdrawn through a pipe 36. Any excess powdered iron which may be mixed with the liquid ferrocobalt condensed in the cooling chamber 28 is carried with it into the separator 35 where it settles out from the liquid and falls into a collector 37. Any unreacted carbon monoxide gas which may pass into the separator flows upwardly around baffles 38 and flows out through a pipe 39.

In the operation of the apparatus which has been described, the rates at which the carbon monoxide gas and the iron enter the reaction chamber are controlled by the needle valves 13, 14 and one of the gates 23 in such manner that the proportion between the amount of iron and the amount of carbon monoxide gas introduced is slightly in excess of that required to form ferro-pentacarbonyl ($Fe(CO)_5$), namely, 3.46 pounds of iron for each 8.5 pounds of carbon monoxide. The slight excess of iron is desirable in order to avoid any danger of forming ferro-noncarbonyl ($Fe(CO)_6$).

The apparatus described is provided with means for accurately controlling the temperature of the reaction chamber. For this purpose, the reaction chamber is provided with heat insulation 40 with a temperature-indicating thermocouple 41. The pipes 16 and 18 leading to the nozzles 11 and 12 are provided with heating coils 42 and with thermocouples 43 to indicate the temperature at which gas is introduced into the nozzles.

While the reaction will take place at room temperature, best results are obtained when the temperature in the reaction chamber is maintained at about 200° F. Higher temperatures, such as 400° F., may be used but do not give any further advantage.

In the modification shown in Fig. 3, an injection pipe 44 is directed into a cylindrical bulge 45 in the wall of the reaction chamber. The inner wall of this bulge forms a deflector which creates

a vortex in the bulge, as shown in Fig. 3. As a result, a high velocity stream of carbon monoxide gas and entrained iron particles issuing from the injection pipe 44 impinges upon a stream directed across the first stream by the deflector. This, like the impact between the streams from the two nozzles of Fig. 2, produces a rapid reaction between the iron particles and the gas.

What I claim is:

1. A method of making metal carbonyl, which comprises directing two high velocity jets of carbon monoxide gas into a reaction chamber, introducing powdered metal into at least one of the jets, and impinging the two jets directly upon each other so as to break up the powdered metal and bring the gas into intimate contact with the metal causing a rapid reaction between them producing metal carbonyl gas.
2. A continuous method of making ferro-pentacarbonyl, which comprises continuously directing two high velocity jets of carbon monoxide gas into a reaction chamber, continuously introducing powdered metal into at least one of the jets and impinging the two jets directly upon each other so as to break up the powdered metal and bring the gas into intimate contact with the metal causing a rapid reaction between them producing gaseous iron carbonyl, continuously withdrawing from the reaction chamber the gaseous carbonyl and any excess iron and carbon monoxide gas, condensing the gaseous carbonyl into liquid carbonyl, and separating the liquid carbonyl from any excess iron and any unreacted carbon monoxide gas, the rates at which the powdered iron and carbon monoxide are introduced being regulated to provide a slight excess of iron in order to avoid producing ferro-nonacarbonyl.
3. The method claimed in claim 2 in which the reaction chamber is maintained at a temperature of approximately 200° F.

JOHN V. FILL.
